(57) CLAIM

The ornamental design for a cargo bed extension for a pick-up truck, as shown and described.

DESCRIPTION

FIG. 1 is a perspective view of a cargo bed extension for a pickup truck, showing my new design, shown in its position of use. The broken line showing of the truck is for illustrative purposes only and forms no part of the claimed design. The pattern shown randomly applied in FIG. 1 is understood to be repeated throughout the surface of the extension as shown in the other views.

FIG. 2 is a rear end elevational view of the cargo bed extension for a pick-up truck shown in FIG. 1.

FIG. 3 is a left side view of the cargo bed extension for a pick-up truck shown in FIGS. 1 and 2.

FIG. 4 is a top view of the cargo bed extension for a pick-up truck shown in FIGS. 1-3.

FIG. 5 is a front end view of the cargo bed extension for a pick-up truck shown in FIGS. 1-4; and,

FIG. 6 is a bottom view of the cargo bed extension for a pick-up truck shown in FIGS. 1-5.
